FREDERICK E. STANLEY, OF WATERBURY, CONNECTICUT, ASSIGNOR TO SCOVILL MANUFACTURING COMPANY, OF WATERBURY, CONNECTICUT, A CORPORATION OF CONNECTICUT.

BUTTON-FEEDING MECHANISM FOR BUTTON-SETTING MACHINES.

1,177,905.

Specification of Letters Patent.

Patented Apr. 4, 1916.

Application filed August 5, 1915. Serial No. 43,849.

To all whom it may concern:

Be it known that I, FREDERICK E. STANLEY, a citizen of the United States, residing at Waterbury, in the county of New Haven and State of Connecticut, have invented a certain new and useful Improvement in Button-Feeding Mechanism for Button-Setting Machines, of which the following is a full, clear, and exact description.

10 This invention relates to the type of button-setting machine illustrated in the case of Stanley and Leggett, filed May 10, 1915, Serial No. 27,042, and has special reference to the button-turning feature by which the 15 buttons as they come one by one from the hopper or turret through the raceway or chute in an edgewise position, are given a quarter turn so as to present them horizontally to the means by which they are placed 20 in operative relation to the tack or other fastening for attachment to a garment or other article.

The invention herein consists of a reciprocating cut-off or escapement which drops 25 the button edgewise upon the inwardly inclined bottom of a pocket, when by gravity it topples over upon an inclined wing on the ejector, and thereupon upon the retreat of the ejector the button by gravity completes 30 a quarter turn over into the raceway of the ejector and lies horizontally therein, whence it is removed by the forward movement of the ejector and delivered to the means by which it is ultimately placed in position to 35 be set, as I will proceed to explain and finally claim.

In the accompanying drawings illustrating 40 the invention, in the several figures of which like parts are similarly designated, Figure 1 is a side elevation of sufficient of a button-setting machine to illustrate the operation of the present invention. Fig. 2 is a front elevation of the parts shown in Fig. 1. Fig. 3 is a perspective view of the button turner. 45 Fig. 4 is a horizontal section of the button turner taken just above the ejector. Fig. 5 is a vertical section of the button turner taken substantially in the plane of line A B, Fig. 4, but with the ejector moved forward

into a position it would occupy to receive a 50 button in its fall from the cut-off and showing the button in dotted lines.

1 may represent the head of the machine, on which is mounted a main shaft 2, and which may carry a button turret from which 55 extends the button chute 3 and a tack or rivet turret from which extends the tack chute 4 as in the case above referred to. At the end of the button chute is an auxiliary chute 5, having a transverse raceway 6 in 60 which is arranged the cut-off or escapement 7, having an outwardly projecting pin 8 which is connected by a link 9 with a rock-lever 10 pivotally mounted at 11 on some 65 part of the head and terminating in a cam-roller 12 which is actuated by a cam 13 on the main shaft 2 and a spring 13^x in such way as to reciprocate the cut-off or escapement to move its slot 14 first into alinement with the chute slot 15 and then into alinement with the pocket 16 formed in the auxiliary chute 5. The bottom of this pocket is provided with a beveled portion 17. Next to the bottom of the pocket is a base-plate 18 having a raceway 19 in which is a reciprocating slide 20, preferably provided with an outwardly inclined wing 21. This slide 20, herein designated the ejector, is provided with a screw threaded extension 22 on which is adjustably secured a grooved collar 23 80 which is engaged by a tracker 24 swiveled in a lever 25 which is pivoted at 26 in connection with the head and at its other end is provided with a cam-roller 27 which is acted upon by a cam 28 on the main shaft 2 and 85 a spring 28^x to vibrate said lever and thereby impart a longitudinally reciprocating motion to the ejector.

The leading end of the ejector may be provided with a finger 29. 90

The discharge end of the auxiliary chute may be cut away or grooved at 30 and 31 to receive a button.

As indicated in Fig. 3, the button 32 descends the chute on edge and falls into the 95 escapement 7 in this position and then when the escapement is moved to the right, Fig. 3, the button drops from the escapement into

the pocket 16 and its edge striking upon the beveled portion 17 the button gravitates outwardly. In the operation of the machine the ejector at this time stands with its wing 21 opposite the button and the button topples over, hub down, against the wing, as indicated by the dotted lines in Fig. 5, and then the ejector is moved to the left so as to remove its wing from its button supporting position, whereupon the button falls, hub down, into the recess or groove of the auxiliary chute in advance of the ejector, and thereafter the ejector is moved to the right and pushes out the button into the means 15 by which it is carried and held in position to receive the tack or rivet or other attaching or fastening medium. The finger 29 projecting slightly over the leading end of the ejector extends over the top of the button and insures the proper engagement of the ejector with the button and its discharge.

Any suitable button transferring mechanism for receiving the button from the ejector and presenting it to the fastener may be used, such, for example, as that explained in the case hereinabove referred to. The tack feed and its appurtenances also may be as in the case hereinabove referred to; but 30 for convenience of reference, I have shown herein the button transferring mechanism as comprising a button holder 33, and I have shown the reciprocating setting anvil 34 and the tack placing and setting mechanism 35, all substantially as in the case referred to, the novel feature of the present invention comprising the turner, as already stated.

The wing 21 may or may not be used, as desired, although it is an efficient means for 40 insuring the proper positioning of the button for its ejection from the chute to the button holder by which it is presented to the setting mechanism, it being understood that the button in order to be set must be turned 45 from its edgewise position incident to its descent in the button chute to a horizontal position with its face up and hub or shank down, as shown in dotted lines in Fig. 4. It is within my invention also to omit the beveled portion 17, but it is advisable to employ either the beveled portion 17 or the wing 21, in order to insure the toppling over of the 50 button from its edgewise to its horizontal position, and both the beveled portion and the wing may be used. These and other variations are within the spirit and scope of the claimed invention.

What I claim is:—

1. In a button setting machine, a button chute down which the buttons descend edge-wise, and an auxiliary chute at the discharge 60 end of the button chute having a pocket communicating with the button chute, a cut-off or escapement interposed be-

tween said pocket and the button chute to transfer the button from the button chute to the pocket, a beveled element onto which the button falls in its escape from the button chute and which causes the button to gravitate from its edgewise to a horizontal 70 position, and means to eject the button from the auxiliary chute.

2. In a button setting machine, a button chute down which the buttons travel edge-wise, and an auxiliary chute at the discharge 75 end of the button chute having a button receiving pocket, a cut-off or escapement interposed between said pocket and the button chute to transfer the button from the button chute to the pocket, and a beveled element in the bottom of the pocket on which the button is dropped from the cut-off or escapement to assist gravity in turning the button from an edgewise to a horizontal position in the bottom of said auxiliary chute, 80 and a horizontally reciprocating ejector arranged in the bottom of the auxiliary chute and operating in line with the horizontally placed button.

3. In a button setting machine, a button chute down which the buttons travel edge-wise, and an auxiliary chute at the discharge 90 end of the button chute having a button receiving pocket, a cut-off or escapement interposed between said pocket and the button 95 chute to transfer the button from the button chute to the pocket, and a beveled element in the bottom of the pocket on which the button is dropped from the cut-off or escapement to assist gravity in turning the button from an edgewise to a horizontal position in the bottom of said auxiliary chute, 100 and a horizontally reciprocating ejector arranged in the bottom of the auxiliary chute and operating in line with the horizontally placed button, said ejector having a button 105 engaging finger on its leading end.

4. In a button setting machine, a button chute down which the buttons travel edge-wise, and an auxiliary chute at the discharge 110 end of the button chute having a button receiving pocket, a cut-off or escapement interposed between said pocket and the button chute to transfer the button from the button chute to the pocket, and a longitudinally reciprocating ejector arranged in the auxiliary chute next to the pocket and provided with an outwardly inclined wing 115 against which the button topples by gravity preparatory to turning over horizontally. 120

5. In a button setting machine, a button chute down which the buttons travel edge-wise, and an auxiliary chute at the discharge 125 end of the button chute having a button receiving pocket, a cut-off or escapement interposed between said pocket and the button chute to transfer the button from the button chute to the pocket, said pocket being

provided with means to assist gravity in turning over the button, and a horizontally reciprocating ejector arranged in a guideway alongside of the pocket and provided with 5 an outwardly inclined wing against which the button falls, said ejector first moving away from the button and permitting it to fall flat across the path of movement of the

ejector and then moving forward to eject the thus fallen button.

In testimony whereof I have hereunto set my hand this 29th day of July, A. D. 1915.

FREDERICK E. STANLEY.
